UNITED STATES PATENT OFFICE.

SAMUEL J. SILL, OF BUFFALO, NEW YORK, ASSIGNOR OF ONE-HALF TO HERBERT H. HEWITT,
OF BUFFALO, NEW YORK.

VULCANIZING-MANDREL FOR RUBBER HOSE.

No. 897,309.

Specification of Letters Patent.

Patented Sept. 1, 1908.

Application filed January 8, 1908. Serial No. 409,773.

To all whom it may concern:

Be it known that I, SAMUEL J. SILL, a citizen of the United States, residing at Buffalo, county of Erie, and State of New York, have 5 invented certain new and useful Improvements in Vulcanizing-Mandrels for Rubber Hose, of which I do declare the following to be a full, clear, and exact description, reference being had to the accompanying drawing, forming part of this specification.

The present invention has for its object to provide an improved construction of mandrel for sustaining sections of rubber hose during the vulcanizing operation.

15 The object of the invention is to provide a mandrel of simple and effective construction which will determine with exactness the length of the hose section and which will also give the desired square finish to the ends of 20 the hose section.

In the drawings, Figure 1 is a view in elevation of the improved mandrel with a hose section thereon and with its removable cap detached therefrom. Fig. 2 is a similar view 25 partly in section and with the removable cap in position. Fig. 3 is a detail section on line 3—3 of Fig. 4. Fig. 4 is a detail section on line 4—4 of Fig. 2.

The body 1 of the mandrel is a hollow tube 30 of iron or steel and at or adjacent one of its ends is fixed a collar 2, this collar being held in position as for example by a rivet 3 that passes through the collar and through the mandrel. The opposite end of the mandrel 35 is formed with a slot 4 extending inward to some distance from the end of the mandrel, this slot 4 being formed with an angular portion 5 and a short reverted portion 6. The mandrel is of suitable size to fit within the 40 section of hose 7 that will be placed upon the mandrel and over the slotted end of the mandrel will be slipped a detachable retaining sleeve or collar 9 that is provided with the inwardly projecting pin 10 adapted to 45 enter the slotted end of the mandrel. It will thus be seen that the sleeve or collar 9 is detachably connected to the mandrel by a bent joint which will enable the cap to be readily placed in position for use and easily withdrawn and which will securely retain the 50 hose in position upon the mandrel during the vulcanizing operation.

When the mandrel is to be used, a section

of hose 7 will be slipped over the mandrel until the end of the hose bears against the 55 fixed collar 2. The detachable collar 9 will then be slipped over the slotted end of the mandrel, the pin 10 passing along the slot 4 and by means of the collar 9 the hose will be slightly compressed so as to permit the pin 60 10 to pass by the angular portion 5 into the reverted portion 6 of the slot, the elasticity of the hose serving to hold the pin 10 in the outer end of the slot 6. The pressure of the 65 collars 2 and 9 upon the ends of the hose section will give to these ends a square shape and will prevent the escape of the rubber during the vulcanizing operation. The slot in the end of the mandrel and the pin 10 in the detachable cap 9 will determine with 70 exactness the length of the hose section. Thus for example, if in making sections for air brake hose the specifications call for sections 75 22 inches long, then the distance between the inner ends of the collars 2 and 9 (when the pin 10 of the collar 9 is at the end of the slot 6) will be exactly 22 inches. After the hose has been vulcanized, and the wrapper removed therefrom, the collar 9 can be easily withdrawn by forcing it inward 80 slightly and turning it upon the mandrel so as to permit the pin 10 to pass from the open end of the slot 4.

It is obvious that the exact details set forth may be varied without departure from 85 the essentials of the invention.

Having thus described my invention what I claim as new and desire to secure by Letters Patent is:

1. A vulcanizing mandrel for rubber hose 90 comprising a cylindrical body having a fixed collar at one end and having at its opposite end a collar removably encircling said mandrel and detachably interlocked therewith.

95 2. A vulcanizing mandrel for rubber hose comprising a body having a fixed collar at one end and having a detachable collar at its opposite end, said detachable collar being connected by a bayonet joint to the body 100 of the mandrel.

SAMUEL J. SILL.
